UNITED STATES PATENT OFFICE.

ALFRED H. BRAECKLEIN, OF BALTIMORE, MARYLAND, ASSIGNEE, BY MESNE ASSIGNMENTS, TO JOSEPH F. HINDES AND GEORGE ARNOLD FRICK, TRUSTEES, BOTH OF BALTIMORE, MARYLAND.

INHALER.

Application filed April 9, 1925, Serial No. 21,944. Renewed October 10, 1927.

This invention relates to inhalers of the type disclosed in my co-pending application Numbered 2,026, filed January 12, 1925.

An object of the present invention is to improve and simplify the device disclosed in the said application, without sacrificing any of its advantageous features and to provide positive means for administering an exact dose of chlorine gas in measured quantities at each treatment.

With the above and other objects in view, the invention further includes the following novel features and details of construction, to be hereinafter more fully described, illustrated in the accompanying drawings and pointed out in the appended claims.

In the drawings:—

Figure 1 is a sectional view partly in elevation showing an inhaler constructed in accordance with the invention.

Figure 2 is a perspective view of the device with the mask removed.

Referring to the drawings in detail where-in like characters of reference denote corresponding parts, the reference character 10 indicates a casing which while preferably made of glass, may be of other suitable material. This casing includes a hollow substantially cylindrical portion defining a mixing chamber 11, while extending from one end of and communicating with this chamber is a hollow extension 12 which is open at its outer end and which provides an air inlet passage 13. A hollow extension 14 projects from the opposite end of the chamber 11 and provides an outlet passage 15 which is open at its outer end and which is in communication at its inner end with the chamber 11.

Extending downwardly from the top of the chamber 11 and spaced from the walls of the latter is a container 16. The walls of this container are tapered and a similarly tapered plug 17 closes the upper end of the container. This plug is provided with a skirt 18 having an opening 19 therein and the latter is adapted to be moved into and out of register with an opening 20 provided in the walls of the container 16. By rotating this plug, communication between the container 16 and the mixing chamber 11 may be controlled. The plug is provided with an operating knob 21 and with an indicator 22,

the latter being adapted to cooperate with graduations 23 provided in the top of the casing 10. By setting the indicator in accordance with these graduations, the degree of opening between the container 16 and the mixing chamber may be accurately regulated.

The container is adapted to receive the chlorine gas and in order to accurately regulate the dose, the gas is preferably sealed with an ampoule indicated at 24, the latter containing a measured quantity of the gas. This ampoule is preferably weakened as indicated at 25 so that it may be broken at this point and placed within the container. An accurate dose of the gas is thus assured.

Frictionally engaging the extension 14 is a mask 26. This mask may consist of a paper cone of a suitable character so that a separate mask may be supplied for each patient if desired, or, they may be renewed when necessary. The masks may also be made of rubber and may be easily sterilized. Any suitable means may be provided for holding the mask in place, such as tapes or straps 27.

The mask is placed over the nose and mouth of the patient, the inhalations drawing in to the mask a measured quantity of gas and air, the amount of gas being regulated by the adjustment of the plug 17, 0.015 milligrams per litre providing a proper concentration. The inhalations of the patient provide a backing up or whirling effect of the air and gas within the chamber 11 so that a thorough mixture is effected.

The invention is susceptible of various changes in its form, proportions and minor details of construction and the right is herein reserved to make such changes as properly fall within the scope of the appended claims.

Having described the invention what is claimed is:—

1. An inhaling device comprising a casing, a mixing chamber included therein, an open top chamber located within and spaced from the walls of the mixing chamber and defining a container, said container having an opening in one wall for communication with the mixing chamber, a plug for closing the top of the container, a skirt extending from the plug, said skirt having an opening

therein adapted to be moved into and out of register with the first mentioned opening to control communication between the container and mixing chamber, an air inlet 5 communicating with the mixing chamber, an outlet also communicating with said chamber and a mask communicating with the mixing chamber through the outlet.

2. An inhaling device comprising a casing, a mixing chamber included therein, an open top chamber located within and spaced from the walls of the mixing chamber and defining a container, said container having an opening in one wall for communication 15 with the mixing chamber, a plug for closing the top of the container, a skirt extending from the plug, said skirt having an opening therein adapted to be moved into and out of register with the first mentioned opening to control communication between the container and mixing chamber, hollow tubular extensions projecting from and communicating with the mixing chamber at the bottom thereof and providing an air 25 inlet, an outlet passage extending from the mixing chamber adjacent the top thereof and diametrically opposite the air inlet, and a mask surrounding the outer open end of the outlet passage.

30 3. An inhaling device comprising a mixing chamber, a cylindrical container within

and spaced from the sides and bottom of said chamber, an air inlet at one side of and adjacent the bottom of said chamber, an outlet at the opposite side of and adjacent the top of said chamber, an opening intermediate the ends of said container in the side wall thereof opposite said outlet and communicating with said chamber.

4. An inhaling device comprising a mixing chamber, a container within and spaced from the sides and bottom of said chamber, an air inlet at one side of said chamber, an outlet at the opposite side of said chamber, an opening in the side wall of said container 45 opposite said outlet and communicating with said chamber, said opening being substantially removed from the bottom of said container.

5. An inhaling device comprising a mixing chamber, a cylindrical container within and spaced from the sides of said chamber, a tubular air inlet projecting from and communicating with the mixing chamber at one side of and adjacent the bottom of said mixing chamber, an outlet at the opposite side of said chamber, an opening intermediate the ends of said container in the side wall thereof opposite said outlet and communicating with said chamber.

In testimony whereof I affix my signature.

ALFRED H. BRAECKLEIN.
